UNITED STATES PATENT OFFICE.

JASON C. LOTTERHAND, OF NEW YORK, N. Y.

COMBINED ADDING AND TYPE-WRITING MACHINE.

No. 811,157.

Specification of Letters Patent.

Patented Jan. 30, 1906.

Application filed July 30, 1903. Serial No. 167,527.

To all whom it may concern:

Be it known that I, JASON C. LOTTERHAND, a citizen of the United States, and a resident of New York, in the county of New York and State of New York, have invented certain new and useful Improvements in a Combined Adding and Type-Writing Machine, of which the following is a specification.

This invention relates to an adding-machine adapted to be independent of but placed adjacent to a type-writing machine and provided with intermediate mechanism whereby the adding-machine becomes temporarily and so long as the connections are maintained an integral part of the type-writing machine.

Heretofore calculating mechanisms have been attached to type-writing mechanisms to form a part thereof; but they were not, so far as known to me, separable therefrom and were not adapted to be used with other type-writing mechanisms of different construction. In this invention, on the contrary, the adding mechanism is adapted to be actuated by any type-writing mechanism comprising numeral-keys, with slight changes conforming merely to the variations of the key connections on the type-writing machine. The adding-machine which it is preferred to use in this connection is the one on which Letters Patent of the United States No. 718,486 were issued to me January 13, 1903, and reference is made to that patent for a detailed description of the parts of that mechanism in which no alteration has been made, and this description will not be repeated here.

It has been found most convenient in practice to place the type-writing machine above the adding-machine mechanism, so that the former mechanism rests upon the casing or frame carrying the latter mechanism; but while it is essential that the two mechanisms should be adjacent this particular relation is not necessary, as they might be differently placed and yet fall within the scope of the invention. The invention will be described assuming the mechanisms to be placed in these relative positions.

In the drawings, Figure 1 is a side elevation and partial vertical section of the type-writing and adding mechanisms and their connections. Fig. 2 is a partial horizontal section and a plan view of some of the parts. Fig. 3 is a rear elevation of the combined mechanisms. Figs. 4 and 5 are details of the

denomination mechanism. Fig. 6 is a detail of the type-writer key-lever finger. Fig. 7 is an enlarged top plan view of the rear ends of the oscillators beneath the plane of the springs 79. Fig. 8 is an enlarged rear elevation of the parts shown in Fig. 7, concealed parts being shown in dotted outline. Fig. 9 is an enlarged side elevation of the parts shown in Figs. 7 and 8. Fig. 10 is an enlarged top plan view of the mechanism at the rear of the machine directly beneath the type-writer key-levers. Fig. 11 is an enlarged detail view of the parts shown on a smaller scale in the lower right-hand corner of Fig. 1. Fig. 12 is an enlarged elevation of the parts relating to the adding mechanism shown mainly in dotted outline in Fig. 1. Fig. 13 is an enlarged perspective view of the parts shown in Fig. 10 looking from the rear at the right and above with the casing removed. Fig. 14 is a detail perspective view of the universal frame. Fig. 15 is a detail sectional elevation of the rear end of a denominational oscillator and adjacent parts. Fig. 16 is a detail top plan view of substantially the same parts. Fig. 17 is a detail rear elevation of the intermediate lever. Fig. 18 is a detail side elevation of the central part thereof. Fig. 19 is a rear elevation of the parts shown in Fig. 13. Fig. 20 is a detail view of part of the mechanism of Fig. 19, and Fig. 21 is a detail view of the leader and intermediate lever.

The type-writing mechanism shown is what is known as the "Underwood," but any other practical mechanism may be substituted therefor.

In the drawings, 10 is the adding-machine of the construction referred to, and 11 is its casing. The only alteration made in this construction is that the key-tops are removed and the key-stems are adapted to be oscillated. The adding mechanism is set in a supplementary casing 20, consisting of a rear wall 21, side walls 22, a bottom 23, coincident in part with the bottom of the casing 11, and a top 24, provided with two apertures, one, 24^a, near the front to permit of the passage of the type-writer numeral-key levers or their fingers, as the case may be, and the other, 24^b, near the rear to permit of the passage of the lower portion of the universal frame.

The type-writing mechanism 30 (hereinafter called the "type-writer") is of usual form and provided with keys, a platen-roller,

carriage, ink-ribbons, and the other parts common and necessary to machines of this character and needs no further or particular description.

5 As has been stated above, the adding-machine is unchanged except for the removal of the key-tops and the adaptation of the key-stems to be oscillated. It is necessary to provide an operating mechanism intermediate the type-writer keys and the stems of the adding-keys to actuate the latter. This mechanism consists, primarily, of two parts—first, means adapted to reciprocate the adding-key stems consisting of digit-bails transversely hinged across their tops, and, second, means for moving the digit-bails consisting of fingers or extension-pieces attached to the type-key levers and adapted to strike the digit-bails as the type-bars are depressed.

10 15 20 25 30 35 The digit-bails 40 each consist of a straight bar 41, passing above the tops of the adding-key stems 200 and suspended by members 43 43, mounted in bearings in the sides of the casing 21 and held in an upward position by a coiled spring 44 against a stop-bar 45, mounted between two of the combs 46. This spring 44 passes around an arm 47, secured to one of the members 43. These digit-bails correspond in number to the nine rows of the adding-key stems, each bail being adapted to actuate that one of the series of key-stems beneath it corresponding in value to the type-writer key depressed.

It might be possible so to construct a type-writer that the numeral-keys could be arranged when depressed to directly strike the digit-bails; but no standard machine is made that way. It is therefore necessary to provide means interposed between the type-writer keys and the digit-bails which will insure the depression of the latter when the proper digit type-writer key is depressed and which will not act upon the bails at all when any key other than a numeral-key is depressed. Such means in the mechanism illustrated consist of the fingers or extension-pieces 420, which may be made of any suitable size and material so long as they are secured to the type-writer key mechanism and extend from some one of its moving parts to such a position with respect to the proper bail that when depressed it will depress such bail. The form of the finger illustrated consists of two leaves 421 and 422, adapted to embrace the key-lever and to be retained in position thereon by its own inherent elasticity.

60 65 70 75 80 85 90 95 100 105 110 115 120 125 130 The keys of the adding-machine are slightly different in construction from the form shown in the Letters Patent No. 718,486 above referred to. These fingers are preferably made removable in order that the type-writer may be restored to its original condition if it is no longer desired to employ the adding mechanism in connection therewith; but when once

the fingers are in place they must be rigid in order to accomplish their purpose, and if it is intended always to use the adding mechanism with the particular type-writing machine they may be made integral with the numeral-keys. The key-stems 200 (best shown in Fig. 1) are each vertically slotted at 201 near their upper extremity and are narrowed at 202 to admit of the passage of the digit-bails between them. The converging oscillators 450 (presently to be described) are each provided with a series of projecting pins 451, engaging in the slots 201, so that when any one of these oscillators is moved forward the entire row or denomination of adding-key stems 200 corresponding to this oscillator is swung forward to bring the narrow tops 202 underneath the series of digit-bails, so that when any one of the latter is depressed by the depression of a type-writer numeral-key the corresponding adding-key stem is depressed. The converging denomination oscillators 450 are long bars, nine in number, supported in a series of combs 46, transversely mounted across the frame of the casing 11 and the reciprocation of which oscillators swings the row of corresponding key-stems into actuating position. The adding-key stems 200 are normally out of an operative position, being so arranged that when any bail is depressed it passes freely between their upper extremities. It is necessary, therefore, to provide means for bringing them into such a position that their tops shall be brought into line with the type-writer key-fingers and the digit-bails before a digit-bail is depressed. For this purpose there is provided a universal frame 50, consisting of a bar 51, supported at the extremities of a pair of bell-crank levers 52 52, mounted on opposite sides of the frame 210, and a rod 53, supported at the other extremities of the same levers 52 52, which are hinged to swing on suitable journal-pins 54, secured to the frame 21 or formed thereon. There is also provided a carriage 60, which in the form illustrated travels on wheels 61 61, mounted between rails 62 62, secured in any suitable manner to the frame 21 and which is provided with ears 63 63, forming bearings for a pivot 64, on which is swung a lever 65. The lower end of this lever hangs near to the rod 53, and the upper end of it is forked at 66 to carry a finger 67, which is adapted to be brought into contact with that one of the converging oscillators which is selected by the denomination-lever presently to be described. The type-writer carriage and the carriage 60 each moves an identical distance at each step, and consequently the finger 67 if rigidly secured to the carriage 60 would strike the next denomination-oscillator before the type-writer had finished its stroke, because while the center lines of the oscillators are the same distance apart as the successive positions of

the carriage, yet the finger 67 if projected into the space between the oscillators would, owing to the thickness of the oscillators and the consequent reduction of the space between them, strike the denomination-oscillator next to that upon which the finger had last delivered its stroke and from which it was being withdrawn. To obviate this, the fork 66 is provided. This fork carries a transverse bar 660, around which is coiled a spring 661 to afford a laterally-yielding bearing for the arm 67 until the latter has had time to return to its proper position to strike the next denomination-oscillator to record the next digit in the series. It is obvious by means of this mechanism that when the bar 51 of the universal frame 50 is depressed, for example, by the downward movement of any of the type-writer key-levers the rod 53 will be swung to contact with the lower member of the lever 65, the finger 67 will be moved forward, and if the carriage is in position will move that one of the converging oscillators in line with it forward to bring the adding-key stems and digit-bails into line. The bar 51 is depressed by the downward motion of any of the type-writer key-levers, as they all are brought into contact with it. Therefore the lever 65 will be constantly reciprocated as the type-writer keys are moved; but this has no effect upon the adding mechanism unless the type-writer carriage is in a proper position. When the movement of the bar 51 is caused by the depression of any of the type-writer numeral-keys, the parts are so constructed and their movements are so timed that the oscillator is moved to place the key-stems in alinement before the finger 420 on that particular type-writer key has struck the digit-bail to depress the proper adding-key stem.

The means employed to place the carriage 60 into the proper actuating position so that the converging oscillator required to swing forward the desired adding-key stems be in operative position are as follows: A series of levers 70 70, (called "denomination-levers" on account of their peculiar function,) corresponding in number and position with the series of converging oscillators, are each pivotally mounted in suitable bearings on the front of the frame, being normally held outward by coiled springs 71. A leg 72 of any one of the levers 70 is adapted to be brought into contact with a pin 73, projecting laterally from the converging oscillator, and thus to move this oscillator toward the front of the machine. Each oscillator is provided with a projecting pin 74 or similar means for engaging with one of the oscillating levers 75, (one being provided for each oscillator,) hinged to swing upon a pivot 76, secured to any suitable point in the framework, so that when the denomination-lever 70 is moved the lever 75 is moved a corre-

sponding distance, a coiled spring 750 serving to retract it to place and spacing-collars 751 keeping the levers 75 apart. Supported in fixed guides 77 77 in the frame of the machine are placed a series of oscillating stop-bars 777, one for each converging oscillator. Each bar 777 is notched at 78 to receive the lower extremity of the lever 75, and each bar is reciprocated as the lever 75 is swung. The converging oscillators are placed at the front end of the machine to coincide with the position of the rows of the adding-key stems and are then deflected and caused to converge, so that at the rear end they are spaced to coincide with the teeth of the rack of the type-writer carriage. A coiled spring 79, secured to each oscillator and to a fixed part of the frame, serves to retract it to position after it has been moved. Any oscillating stop-bar 777 being thrown out of alinement and beyond the plane of its normal position when at rest by the action of the lever 75, the oscillator and the denomination-lever is then thrown in the path of a lug 68, forming part of the carriage 60, and prevents its further movement toward the left, Figs. 3, 10, 13, 16, and 19.

It is obvious that the space on the paper in the type-writer on which are recorded the impressions of the numeral type-bars whose levers can be actuated to set in operation the adding-keys constitutes a zone within the area of which the adding mechanism and the recording mechanism of the type-writer have become united and that the position of such zone varies with respect to the paper in the type-writer at the will of the type-writer operator who may desire to add numbers recorded at any part of the sheet. The means employed to control the position of this adding zone are as follows: A rail 80 is secured to the type-writer carriage by two brackets 81 81, in which it is journaled to swing on trunnions 82 82 to permit of its passing by the intermediate lever (presently to be described) upon the return of that carriage. Mounted upon the rail 80 is a movable leader 83, consisting of a front flat member 84 and a rear member 85, the groove being adapted to embrace the rail. A beveled lug 86 on the inside of the leader 83 is secured to or made integral with the member 85 to engage with the intermediate lever. It is also provided with a toothed lock 87, adapted to be placed in and out of engagement with the teeth on the rail by a yielding button 88, secured to its outer extremity and projecting from the face of the leader 83. By this means the leader 83 can be set in position along the type-writer carriage and retained in such position after adjustment.

An intermediate lever 90 is pivotally mounted upon a hub 91, secured to a bracket 92 or any suitable fixed part of the rear frame of the type-writer. This lever 90 is

composed of two members, the outer one 93 being movable upon the inner one 94 by means of slots 95 95 and stops 96 96. This arrangement provides a means for releasing the lever 90 from its engagement with the leader 83 when the carriage is about to pass out of the adding zone. The upper end of the outer member 94 of the lever 90 is so placed that it is within the path of the leader 83 as the carriage of the type-writer is moved to the left of the operator and is adapted to be intermittently moved upon its pivot as the carriage moves step by step. The lower end of the inner member 94 of the lever is pivoted at 940 to a link 610, secured to the carriage 60 by a stud 611. From this it is evident that as the leader 83 moves step by step to the left the carriage 60 must also move step by step to the right. This carriage, however, it will be remembered, carries the finger 67, which moves the converging oscillator of the highest denomination selected to be recorded to bring the adding-key stems in coincidence with the type-keys to register the values recorded by the latter. Therefore the position of the leader 83 determines the position upon the paper transported by the carriage of the type-writer at which the numbers to be registered by the adding mechanism are recorded, or, in other words, it fixes the position laterally of the adding zone, the longitudinal position of this zone being fixed by the rotation of the paper-carrying platen. The member 93 is also the releaser for the lever 90 and locking device for the keys, hereinafter described.

The intermediate lever 90, the carriage 60, and adjacent parts are in an operative position, as illustrated in Fig. 3, and after the numbers have been written upon the paper and thus recorded and the appropriate adding-key stems have been simultaneously actuated to register such numbers the operating-bar 100 of the adding mechanism is actuated to produce the total of the different numbers recorded, which total is displayed upon the appropriate wheels, as described in the patent above referred to, and may then be read off and written upon the type-writer in the usual manner.

A bar-lever 110, Figs. 1, 11, and 12, is fulcrumed at about its mid-length to any suitable part of the machine-frame and is secured to or made integral with the adding-bar 100 at its front end. At its rear end it is provided with a pin 111, which engages in a fork 113 of a lever 112, pivoted at about its mid-length and which at its rear end is provided with a transverse rod 114, supported at its other end by a crank 115, suitably pivoted. This rod 114 is adapted to engage with a hook 98, formed at the lower extremity of the outer member of the lever 90 by bending its parts, as shown in Fig. 17 and in dotted lines 65 in Figs. 1 and 11, to depress the lever 90 and

throw it out of engagement with the leader 83, and thus permit the carriage of the type-writer to proceed and the carriage 60 to be retracted to its normal position.

Transversely mounted to slide in suitable 70 bearings in the frame of the casing 21 is a rod 120, carrying two hooks 121 121, one at each end, rigidly secured thereto and in proximity to the lower members of the bell-crank levers of the universal frame. This rod 120 is longitudinally slotted at 122 to receive a tongue 123, depending from the carriage 60, the slot 122 being so arranged in the rod that the tongue 123 touches one extremity of the slot as the units of cents is recorded, so that the 80 movement of the carriage of the type-writer (and consequently of the carriage 60) one step farther will cause the tongue 123 to move the rod 120 to bring the hooks 121 121 closely to embrace and hold the bell-crank 85 levers, and as these levers determine the motion of the bar of the universal frame, which bar is in contact with all of the key-levers, all of these key-levers are locked against any further movement until the hooks 121 121 90 are moved out of engagement with the frame. The rod 120 is restored to its normal position by the coiled spring 124.

The movement of the operating-bar 100 of the adder is necessary to unlock the parts and 95 permit the writing to proceed. Such movement depresses the operating-bar levers 110, which in turn trips the lever 112 and carries down the transverse rod 114, and this in turn depresses the movable part 94 of the intermediate lever 90 and releases the same to permit the carriage 60 to return to its normal position and the type-writer carriage to proceed.

An air-check is provided to eliminate the 105 shock occasioned by the impact of the type-writer carriage against the intermediate lever 90 whenever the travel of the carriage is considerable before it reaches the lever. This air-check consists of a cylinder 600, secured 110 at a suitable point within the framework, and a loosely-fitting piston 601, adapted to reciprocate therein and which is provided with a piston-rod 602, secured at any suitable point on the carriage 60. If the lever 90 is 115 struck quickly or violently by the movement of the type-writer carriage when the carriage is released and the carriage 60 is thus moved quickly to the left, such movement is taken up by the air-check, which also serves to diminish noise and shock arising from the movement of the carriage 60 or its actuating parts.

At the back of the inner member 94 of the intermediate lever 90 there is a pin 97, to 125 which is attached one end of a spring 988, coiled around the hub 91, the other end of the spring being secured to the bracket 92 at any suitable point, as the pin 99. When the lever 90 is moved by the leader 83, this 130

spring 988 retracts it to its normal position after the type-writer carriage has ceased to be actuated and the adding-bar of the adder has been struck to release the parts of the mechanism, which are locked until this bar is depressed to release them.

To the outer member 93 of the intermediate lever 90 is secured a dependent flaring pinched spring 930, the lower extremities of which 10 embrace the hub 91. When the rod 114 is actuated to pull down the lever 90, this spring 930 is forced down over the hub and is adapted, by reason of its construction at 931, to embrace it in its new position to retain it 15 positively in place, making its movement positive and certain. The oscillating stop-bars 777 are arranged in a series corresponding in number and position to the denominations of the numbers to be recorded and 20 added. A difficulty arises from the fact that the decimal-point must be recorded before the tens of cents when the figures represent monetary values. It is necessary to stop the carriage 60 at the place where this decimal- 25 point must be written. The oscillating stop-bar 777 corresponding to tens of cents is therefore offset at its extremity 778, so that the movement of the type-writer carriage is arrested at that point and the adding operation suspended while the decimal-point is 30 being recorded.

The method of using the machine is as follows: The fingers or extension-pieces 420 are first placed in their proper positions upon the 35 different numeral-levers of the type-writer. The type-writer is then placed above the adding mechanism, a proper registration being secured by placing the rubber feet of the type-writer in depressions 222 in the adding- 40 machine frame, formed therein for that purpose. The bracket 92 is then secured, by screws or whatever other means is provided, to the rear frame of the type-writer, and the rail 80, with the leader 83, is similarly placed 45 in position. The intermediate lever 90 is then swung around and the link 610 is secured to the carriage 60 by means of the stud 611 or what other suitable means has been provided. These operations couple the type- 50 writing mechanism to the adding mechanism. Now let us suppose that it is desired to write on the type-writer, say, three items of an invoice and add the items, and let the items, for instance, be as follows:

55 750 yards of black silk @ \$4.00... \$3,000.00
63 yards of blue silk @ 3.15... 41.36
8 yards of red silk @ 5.17... 298.45

60 The words "750 yards of black silk @ \$4.00" would be written on the type-writer as usual. If the words were begun at 10 on the type-writer scale, "\$4.00" would terminate at 40. It would probably be desirable 65 with a line of that length to have the adding

zone begin at 55 on the scale. The leader 83 would then be set at 55, and thereafter needs no attention. It will be observed that the first item to be added is "\$3,000.00," the highest integer being in the column of units 70 of thousands. After the line has been written to the point above mentioned it is necessary to press inwardly that one of the denomination-levers corresponding to the figure, and in the form of machine illustrated this 75 would be the sixth one, counting from the right, and the fourth one, counting from the left. This movement of the lever 70 draws forward the corresponding converging denominational oscillator 450. This in turn, 80 through the pin 74, moves the oscillating lever 75, which in turn moves in the notch 78 of the stop-bar 777 and projects this bar into the path of the lug 68 on the carriage 60. (See Fig. 9.) If the type-writer carriage is now 85 released, it moves to the left until the leader 83 strikes the intermediate lever 90, which moves the carriage 60 to the right until the lug 68 comes into contact with the particular stop-bar 777 which has been moved by the 90 denomination-lever corresponding to units of thousands, and when then the first figure of the number "3,000" is struck on the type-writer the adding operation is commenced, because the bar 450 having been drawn forward the selected row of adding-key stems 95 have been moved into a vertical position. When, therefore, the numeral-key "3" of the type-writer is depressed, the finger 420, secured to its lever, is moved downward, im- 100 pinging upon the third digit-bail 40 from the front, and depresses it. This in turn strikes that one of the adding-key stems which has been brought into vertical position—that is, the one in the unit of thousands column— 105 and depresses it. When the lever 70 has been pressed and the type-writer carriage released, the carriage 60 is, as has been explained, brought into proper position, so that the type-writer carriage and paper is in such 110 a position that when the first integer of the number is struck it will be in the column appropriate to units of thousands. The operator releases the lever 70 as soon as he observes that the type-writer carriage has 115 moved to its proper position. When the numeral type-writer key-lever is depressed, it depresses the universal frame 50. This in turn presses inward the lever 65 and arm 67, which latter moves forward, strikes 120 against the particular denominational oscillator in front of it, and thus brings the desired adding-key stem in alinement with the proper digit-bail to be moved by the latter when the numeral-key of the type-writer is 125 depressed. The remaining integers of the number "3,000.00" being all zeros and the "0-key" on the type-writer not being provided with an extension finger-piece 420 as these successive zeros are struck and the car- 130

riage 60 moves in step-by-step unison with the type-writer carriage the arm 67 moves forward at each step and moves the corresponding oscillator 450 and throws the proper row 5 of adding-key stems into alinement successively; but as the digit-bails are not depressed nothing occurs to affect the adding-machine, although the successive zeros are written on the paper on the type-writer carriage. Suppose now that the operator being careless or forgetful strikes a numeral-key beyond the column of units of cents or desires to write something—for instance, the word "net"—on the same line. As the last integer of the figure 15 "3,000.00" has been struck, the tongue 123 has been moved forward and the hooks 121 121 have locked the universal frame 50 up against the entire set of key-levers, and therefore the keys cannot be depressed. This calls 20 the attention of the operator to the fact that the numeral has been completely written and that the operating-bar 100 should be actuated. As soon as the bar 100 is depressed the lever 112 is tripped and the movable part 25 94 of the intermediate lever 90 is depressed and the carriage is released to return to its normal position. It will thus be seen that the adding zone terminates at units of cents and that anything may be written on the paper 30 to the right of that zone as soon as the operating-bar 100 has been actuated. The operator then writes the next line of the invoice down to the number "3.15." He then presses the denomination-lever in the column 35 of hundreds and releases the type-writer carriage until the lug 68 brings the carriage to a stop against the stop-bar 777 of the denominational lever affected. He then writes the number "298.45," and as the type-writer 40 carriage moves forward step by step and the carriage 60 moves in unison with it each denominational oscillator 450 is moved in succession by the arm 67 to throw the proper row of adding-key stems into coöperation 45 with the digit-bails as they are successively depressed by the fingers 420 on the numeral-keys, and when the number has been completely written the operating-bar 100 is again depressed. The third line of the invoice is 50 then written, only after the number "5.17" has been written the denomination-lever 70 corresponding to the tens-column is depressed, because the highest integer of the number "41.36" is to be written in that column. After that number has been written and the operating-bar 100 depressed the total 55 of the sums added is read from the registering device provided for that purpose, and the total read from such registry is written beneath the sum added in the usual manner, its 60 proper place in the adding zone on the paper being fixed by pressing the proper denomination-lever corresponding to the highest integer of the total and releasing the type-writer carriage until the stop-bar brings the 65

carriage 60 to rest, and thus fixes the position of the type-writer carriage.

It will be noticed that by means of the mechanism above described it is possible to write on the paper not only beyond the column of figures to be added, but also to write more than one such column of figures with intermediate text on the same horizontal line, because the depression of the actuating-bar of the adding mechanism releasing the intermediate lever 90 from its connection with the movable lever 83 enables the type-writing mechanism to be employed after such release in the normal manner. Another feature of the mechanism is that the strength required 75 to depress the numeral-keys when the adding mechanism is employed is so little, if any, greater than that required for the depression of the ordinary keys that the difference is not noticeable.

What I claim is—

1. The combination with the keys of a type-writer, of the key-stems of an adding-machine located beneath the type-writer and normally out of alinement with the type-writer keys and means for moving them into such alinement.

2. The combination with the keys of a type-writer, of the key-stems of an adding-machine located beneath the type-writer and normally out of alinement with the type-writer keys and means for moving them into such alinement, comprising a series of oscillators corresponding to the denominations of the numbers to be registered and added.

3. The combination with the keys of a type-writer, of the key-stems of an adding-machine located beneath the type-writer and normally out of alinement with the type-writer keys and means for moving into such alinement any row of the adding-machine key-stems corresponding to a desired denomination.

4. The combination with the keys of a type-writer, of the key-stems of an adding-machine located beneath the type-writer and normally out of alinement with the type-writer keys, means for moving into such alinement any row of the adding-key stems corresponding to a desired denomination, consisting of a reciprocating oscillator and means for moving it and limiting such movement.

5. The combination with the key-stems of an adding-machine, of a type-writing machine mounted over the adding-machine and comprising key-levers, key-stems, and key-heads, said type-writer keys having removable laterally-projecting rigid fingers in position to actuate the key-stems of the adding-machine.

6. The combination with the keys of a type-writer, of the key-stems of an adding-machine located beneath the type-writer and normally out of alinement with the type-writer keys and means for moving into such

- alinement any row of the adding-machine key-stems corresponding to the initial denomination of the highest number to be recorded and added.
- 5 7. In a machine of the class described, the combination of the type-writer carriage, a finger-carriage, a lever intermediate the two carriages and adapted to be moved by the former to move the latter, the operating-bar of the adding-machine, means for disengaging the lever from the type-writer carriage brought into operation by the depression of said operating-bar, and means for holding it out of engagement.
- 15 8. The combination with the key-stems of an adding-machine, of the keys of a type-writing machine mounted over said stems whereby when the keys of the type-writer are struck the proper adding-machine key-stems are depressed, means for locating the adding zone at a predetermined point in the movement of the type-writer platen comprising the type-writer carriage, an adjustable leader thereon, a series of denomination-oscillators, means for actuating such oscillators, and a connection between said actuating means and said carriage.
- 25 9. The combination with the key-stems of an adding-machine, of the keys of a type-writing machine mounted over said stems whereby when the keys of the type-writer are struck, the proper adding-machine key-stems are depressed, and means for locking the parts actuated against further movement after the numbers to be added have been recorded by striking the keys of the type-writer.
- 35 10. The combination with the key-stems of an adding-machine, of the keys of a type-writing machine, mounted over said stems whereby when the keys of the type-writer are struck, the proper adding-machine key-stems are depressed, and means for locking the parts actuated against further movement after the numbers to be added have been recorded by striking the keys of the type-writer and releasing the same only upon the completion of the adding operation.
- 45 11. The combination with the keys of a type-writer, of the key-stems of an adding-machine located beneath the type-writer and normally out of alinement with the type-writer keys, means for moving into such alinement any row of the adding-machine key-stems corresponding to a desired denomination, consisting of a reciprocating oscillator and means for moving it and limiting such movement, and a permanent connection between all of the type-writer keys and the row of adding-machine key-stems corresponding to the initial denomination to be recorded.
- 55 12. The combination with the keys of a type-writer, of the key-stems of an adding-machine located beneath the type-writer and normally out of alinement with the type-writer keys, means for moving into such alinement any row of the adding-machine key-stems corresponding to the initial denomination to be recorded, a plurality of permanent connections between all of the type-writer keys and each row of adding-machine key-stems corresponding to different denominations.
- 65 13. The combination with the key-stems of an adding-machine arranged in a series of rows, of the type-writing machine comprising key-levers, key-stems and key-heads mounted over the adding-machine key-stems, a permanently-attached connection located between the type-writer keys and the series of rows of the adding-machine key-stems, and a removable laterally-projecting rigid finger on each key-stem of the type-writer in position to depress said connection when the key is depressed.
- 75 14. The combination with the key-stems of an adding-machine, of the keys of a type-writing machine, mounted over said stems, whereby when the keys of the type-writer are struck the proper adding-machine key-stems are depressed, and means for suspending the adding operation while the decimal-point is being recorded on the type-writing machine comprising a stop-bar offset at a predetermined point to arrest the movement of the type-writer carriage at a corresponding point.
- 85 15. The combination with a type-writer comprising keys and a carriage and an adding-machine provided with key-stems, normally out of alinement with the type-writer keys, of means for moving into such alinement the row of the adding-machine key-stems corresponding to the highest denomination to be recorded and means for thereafter actuating the adding mechanism step by step as the type-writer carriage is moved to record the numbers struck by the type-writer keys.
- 95 16. The combination with a type-writer comprising keys and a carriage, and an adder comprising key-stems and registering mechanism, of means for uniting the two mechanisms simultaneously to record on the carriage and to register in the adder, numbers struck by the type-writer keys, comprising removable fingers on the type-writer keys, means for bringing a selected row of the adder-key stems, normally out of alinement with the type-writer key-fingers, into alinement therewith, and means for thereafter causing the type-writer mechanism and the adding mechanism to act in unison.
- 105 17. The combination with a type-writer comprising keys and a carriage and an adding-machine provided with key-stems, normally out of alinement with the type-writer keys, of means for moving into such alinement the row of the adding-machine key-stems corresponding to the highest denomination to be recorded, means for thereafter actuating the adding mechanism step by step

as the type-writer carriage is moved to record the numbers struck by the type-writer keys, and means for automatically locking both type-writer and adding mechanisms 5 against further movement.

18. The combination with a type-writer comprising keys and a carriage and an adding-machine provided with key-stems, normally out of alinement with the type-writer 10 keys, of means for moving into such alinement the row of the adding-machine key-stems corresponding to the highest denomination to be recorded, means for thereafter actuating the adding mechanism step by 15 step as the type-writer carriage is moved to record the numbers struck by the type-writer keys, means for automatically locking both type-writer and adding mechanisms against further movement and means for releasing 20 the same.

19. The combination with a type-writer comprising keys and a carriage and an adding-machine provided with key-stems, normally out of alinement with the type-writer 25 keys, of means for moving into such alinement the row of the adding-machine key-stems corresponding to the highest denomination to be recorded, means for thereafter actuating the adding mechanism step by step 30 as the type-writing carriage is moved to record the numbers struck by the type-writer keys, and means for automatically locking both type-writer and adding mechanisms against further movement and releasing the 35 same only upon completion of the adding operation.

20. The combination with the keys of a type-writer, of the key-stems of an adding-machine located beneath the type-writer and 40 normally out of alinement with the type-writer keys, and means for moving any row of said key-stems into said alinement consisting of an oscillating bar provided with a flexible connection with each of the key- 45 stems in said row.

21. The combination with the keys of a type-writer, of the key-stems of an adding-machine located beneath the type-writer and normally out of alinement with the type- 50 writer keys and means for moving each row of said key-stems into such alinement, consisting of a plurality of oscillating bars each provided with a flexible connection with each of the key-stems in its row.

22. The combination with the keys of a type-writer of the keys of an adding-machine located beneath the type-writer and normally out of alinement with the type-writer 55 keys and means for moving them into such alinement, whereby when the keys of the type-writer are struck, the proper adding-machine key-stems are depressed, and a reciprocating bail transversely mounted across the rows of adding-key stems and forming a

connection between the type-writer keys and 65 said key-stems, whereby when the corresponding type-writer numeral-key is struck said bail is moved downward to depress the adding-machine key-stems in its path.

23. The combination with the keys of a 70 type-writer, of the key-stems of an adding-machine located beneath the type-writer and normally out of alinement with the type-writer keys, and means for moving them into such alinement, and a plurality of reciprocating 75 bails, each transversely mounted across the rows of adding-machine key-stems, and forming a connection between the type-writer keys and said key-stems, whereby when the corresponding type-writer numeral-key is struck, its bail is moved downward to 80 depress the adding-machine key-stems in its path.

24. The combination with the keys of a 85 type-writer, of the key-stems of an adding machine located beneath the type-writer, and normally out of alinement with the type-writer keys, and means for moving them into such alinement, a reciprocating bail transversely mounted across the rows of adding- 90 key stems and forming a connection between the type-writer keys and said key-stems, whereby when the corresponding type-writer numeral-key is struck said bail is moved downward to depress the adding-machine 95 key-stems in its path, and means for returning said bail to its normal position.

25. The combination with the keys of a type-writer, of the key-stems of an adding-machine located beneath the type-writer and 100 normally out of alinement with the type-writer keys, and means for moving them into such alinement, and a plurality of reciprocating bails, each transversely mounted across the rods of adding-machine key-stems, and 105 forming a connection between the type-writer-keys and said key-stems, whereby, when the corresponding type-writer numeral-key is struck, its bail is moved downward to 110 depress the adding-machine key-stems in its path and means for returning each of said bails to its normal position.

26. The combination with the key-stems of an adding-machine, of the keys of a type-writing machine, mounted over said stems 115 and provided with projecting fingers to actuate the same, each finger consisting of a removable piece rigidly attached to the key-lever and registering with the proper adding-stems.

27. The combination with the keys of a type-writer, of the key-stems of an adding-machine located beneath the type-writer and normally out of alinement with the type-writer keys, and means for moving them into 125 such alinement, a bail placed between each row of adding-machine key-stems having identical numbers with the set of type-writer

keys, each type-writer key being provided with a removable, projecting, rigid fender adapted to register with its bail to depress it.

28. The combination with the keys of a type-writer, of the key-stems of an adding-machine located beneath the type-writer and normally out of alinement with the type-writer keys, and means for moving them into such alinement consisting of a plurality of oscillating bars corresponding in position in front with the rows of adding-machine key-stems and in the rear with the teeth of the rack of the type-writer carriage.

29. The combination with the keys of a type-writer, of the key-stems of an adding-machine located beneath the type-writer and normally out of alinement with the type-writer keys, means for moving them into such alinement comprising a plurality of oscillating bars corresponding in position in front with the rows of adding-machine key-stems and in the rear with the teeth of the rack of the type-writer carriage, and means for moving any one of said oscillating bars.

30. The combination with the keys of a type-writer, the key-stems of an adding-machine normally out of alinement with the keys of the type-writer, and means for moving them into such alinement comprising a series of oscillating bars engaging with the adding-machine key-stems, of a plurality of denomination-levers each adapted to place in position a stop adapted in turn to limit the movement of the means by which the proper oscillating bar is actuated to move the row of corresponding adding-machine key-stems into alinement.

31. The combination with a type-writer comprising keys and a carriage, and an adding-machine comprising key-stems normally out of alinement with the type-writer keys, of means for locking the type-writer keys and carriage against further movement, comprising a universal frame adapted to be held against the type-writer key-levers and a movable catch brought to engage with the universal frame by the movement of the type-writer carriage through intermediate mechanism.

32. The combination with a type-writer comprising keys and a carriage, and an adding-machine, of means for locking the type-writer keys and carriage against further movement, comprising a universal frame adapted to be held against the type-writer key-levers; and a movable catch brought to engage with the universal frame by the movement of the type-writer carriage through intermediate mechanism, consisting of an intermediate lever adapted to be moved by the type-writer carriage, and a carriage connected to and moved by said lever and provided with a tongue which in turn actuates the movable catch against the universal frame.

33. The combination with a type-writer comprising keys and a carriage, and an add-

ing-machine comprising an operating-bar, of means for locking the type-writer keys and carriage against further movement comprising a universal frame to be held against the type-writer key-levers and a movable catch brought to engage with the universal frame by the movement of the type-writer carriage through intermediate mechanism comprising an intermediate lever and means for releasing the parts comprising a lever actuated by the operating-bar of the adding-machine to disengage the intermediate lever from the type-writer carriage.

34. In combination with a type-writer comprising keys, key-levers and a carriage, means for locking the key-levers against further movement comprising a universal frame and a movable catch brought to bear against the said frame through the movement of the carriage of the type-writer to a predetermined point, to actuate the frame against the key-levers.

35. The combination with a type-writer comprising keys, key-levers and a carriage and an adding-machine, comprising key-stems and an operating-bar, of means for locking the key-levers against further movement comprising a universal frame adapted to be brought into contact with all of said key-levers by a movable catch brought to bear against the said frame through the movement of the type-writer carriage, and means for releasing the said parts brought into action by the motion of the operating-bar in the adding-machine.

36. The combination with a type-writer comprising keys, key-levers and a carriage and an adder located beneath the type-writer and comprising an operating-bar, and the key-stems of which are normally out of alinement with the type-writer keys, and which adder is provided with means for moving any row of said key stems into such alinement, of means for locking the type-writer keys against further movement by the same means which throw the key-stems of the adder into alinement with the type-writer keys.

37. The combination with a type-writer comprising keys, key-levers and a carriage, and an adder located beneath the type-writer and comprising an operating-bar, and the key-stems of which are normally out of alinement with the type-writer keys, and which adder is provided with means for moving any row of said key-stems into such alinement, of means for locking the type-writer key-levers against further movement, comprising a universal frame adapted to be brought into contact with all of said key-levers by a movable catch brought to bear against the said frame through the movement of the same means which throw the key-stems of the adder into alinement with the type-writer keys.

38. The combination with a type-writer comprising keys, key-levers and a carriage,

- and an adder located beneath the type-writer and comprising an operating-bar, and the key-stems of which are normally out of alinement with the type-writer-keys, and which adder is provided with means for moving any row of said key-stems into such alinement, of means for locking the type-writer key-levers against further movement, comprising a universal frame adapted to be brought into contact with all of said key-levers by a movable catch brought to bear against the said frame through the movement of the same means which throw the key-stems of the adder into alinement with the type-writer keys, and means for releasing the said parts brought into action by the motion of the operating-bar of the adding-machine.
39. In combination with a type-writer comprising keys and key-levers, and an adder comprising key-stems normally out of alinement with the type-writer keys, means, comprising oscillators, for moving them into such alinement, a carriage carrying a finger, a universal frame actuated by each type-writer key-lever adapted to oscillate said key-lever, and means for moving said carriage into a position in which the finger is oscillated to reciprocate a selected oscillator.
40. In combination with a type-writer comprising keys and key-levers, and an adder comprising key-stems normally out of alinement with the type-writer keys, means, comprising oscillators, for moving them into such alinement, a carriage carrying a finger adapted to be oscillated by the motion of every type-writer key-lever through intermediate mechanism, and means for adjusting said carriage into a position in which the finger is brought opposite the proper oscillator to reciprocate it.
41. In combination with a type-writer comprising keys and key-levers, and an adder comprising key-stems normally out of alinement with the type-writer keys, and means, comprising oscillators, for moving them into such alinement, a carriage carrying a finger adapted to be oscillated by the motion of every type-writer key-lever through intermediate mechanism, and means for adjusting said carriage into a position in which the finger is brought opposite the proper oscillator to reciprocate it, comprising a stop actuated by a denomination-lever at the front of the type-writer.
42. In a machine of the class described, comprising a carriage and a series of adding-key-stem oscillators, the combination therewith, of means for actuating said oscillators comprising a moving finger, and means for bringing said finger opposite any selected oscillator comprising a stop, and one of a series of denomination-levers for moving said stop to position.
43. In a machine of the class described, comprising a carriage and a series of adding-key-stem oscillators, the combination there-
- with, of means for actuating said oscillators comprising a moving finger, provided with a tip adapted to contact with said oscillators, and means for bringing said finger opposite any selected oscillator comprising a stop, and one of a series of denomination-levers for moving said stop to position.
44. In a machine of the class described, comprising a carriage and a series of adding-key-stem oscillators, the combination therewith, of means for actuating said oscillators comprising a moving finger, provided with a tip adapted to yield laterally to a limited extent to bring its longitudinal movement into unison with other moving parts of the machine, and means for bringing said finger opposite any selected oscillator comprising a stop, and one of a series of denomination-levers for moving said stop to position.
45. In mechanism of the class described, comprising a type-writer, its carriage, keys and key-levers, and an adder having key-stems normally out of alinement with the type-writer keys, means for locating an adding zone on the paper of the type-writer carriage comprising a leader adjustably secured to said carriage and adapted to contact with and operate the mechanism whereby the adding-machine key-stems are thrown into alinement with the keys of the type-writer.
46. In mechanism of the class described, comprising a type-writer, its carriage, keys and key-levers, and an adder having key-stems normally out of alinement with the type-writer keys, means for locating the adding zone on the paper of the type-writer carriage, comprising a leader adjustably secured to said carriage, a finger adapted to move any one of a plurality of oscillators into position to bring a row of adding-key stems into alinement with the type-writer keys, a carriage on which said finger is mounted and a connection between the type-writer-carriage leader and the finger-carriage whereby the latter is moved in unison with the former commencing at a point fixed by the position of the leader on the type-writer carriage.
47. In a machine, of the class described, the combination of a series of pivoted key-stem oscillators, means for actuating said oscillators comprising a finger, and a carriage carrying said finger, and means for checking and governing the movement of the finger-carriage laterally of the machine comprising a fluid-cylinder and a piston adapted to reciprocate in said cylinder and connected to said finger-carriage.
48. In a machine of the class described comprising a finger-carriage, the combination of said finger-carriage, a connection adapted to communicate the step-motion of the type-writer carriage, thereto, comprising a lever adapted to engage therewith and with the type-writer carriage, the operating-bar of the calculating-machine, and means for disen-

gaging the connection of the finger-carriage with the type-writer carriage brought into operation by the depression of the operating-bar of the adding-machine.

- 5 49. In a machine of the class described, the combination of a type-writer carriage, a finger-carriage, a connection adapted to engage with both carriages and communicate the step-by-step movement of the one to the
10 other, and means for disengaging the connection with the type-writer carriage comprising

the operating-bar of the adding-machine, the depression of which brings said disengaging means into operation.

Witness my hand, this 24th day of July, 1903, at the city of New York, in the county and State of New York.

JASON C. LOTTERHAND.
